[57] CLAIM

The ornamental design for a skin stapler, as shown and described.

DESCRIPTION

FIG. 1 is a perspective view of a skin stapler, showing our new design in folded condition;

FIG. 2 is a front elevational view thereof;

FIG. 3 is a back elevational view thereof;

FIG. 4 is a top plan view thereof;

FIG. 5 is a side elevational view thereof, of which the opposite side elevational view is identical;

FIG. 6 is a bottom plan view thereof; and

FIG. 7 is a perspective view thereof, in unfolded condition.
